UNITED STATES PATENT OFFICE.

JOHN H. GRAYSON, OF ATHENS, OHIO, ASSIGNEE TO THE J. H. GRAYSON MANUFACTURING COMPANY, OF ATHENS, OHIO, A CORPORATION OF OHIO.

GAS HEATER.

Application filed January 22, 1923. Serial No. 214,274.

To all whom it may concern:

Be it known that I, JOHN H. GRAYSON, a citizen of the United States, residing at Athens, in the county of Athens and State of Ohio, have invented certain new and useful Improvements in Gas Heaters, of which the following is a specification.

This invention relates to gas heaters of the type known as wall heaters.

10 Heaters of this type are set into a wall or a partition between adjacent 2"x4" uprights and secured to these uprights. The problem of satisfying the requirements of the fire underwriters and at the same time 15 producing a construction which is simple and practical is not easy. In the first instance the available space in a partition is not more than 4"-5" deep while it is for practical reasons not desirable to have a construction project a substantial distance outwardly from the surface of the wall. These 20 two limiting conditions make it difficult to make a spatial disposition of the necessary heater elements and the support and at the same time afford adequate fire protection.

It is the special object of this invention to provide a gas heater of the wall heater type which satisfies all practical conditions from the stand point of the user and at the same 30 time meets to the fullest extent the requirements of the fire underwriters and which in addition, to meet a general desideratum, presents an ornamental construction.

For a full understanding of the invention, 35 reference is made to the accompanying drawings in which—

Fig. 1 is a face view of a heater embodying the invention;

Fig. 2 is a vertical section therethrough; 40 and

Fig. 3 is a horizontal section on line 3—3, Fig. 2.

The heater is of the radiant mantle type. 45 A plurality of mantles 10 are supported upon a plate 11 below which is disposed the manifold 12 and the mixing tube 13. The construction of these elements is of the usual type.

The construction of the heater includes an 50 outer pan which consists of a back 14, side walls 15 at right angle thereto, flaring top and bottom walls 16 and flanges 17 extending laterally from the side walls 15.

Carried by this outer or main pan is a second pan comprising a back 18, flaring side

walls 19 and a flaring top wall 20, the bottom being open to provide room for the manifold and mixing tube of the burner. The second pan is supported on the main pan by means of brackets 21 the webs of 60 which extend vertically. The second pan has flanges 22 similar to the flanges 17 on the main pan.

Within the second pan is disposed a third pan which has a back wall 23, side walls 24 65 and a flaring top wall 25, the bottom of which is formed by the plate 11 which is connected to the side walls 24 by means of screws 26. The third pan is secured to the second pan by brackets 27 which are like 70 brackets 21.

A face plate 28 is secured to the flanges 22 and a face plate 29 is secured to the face plate 28 and the flanges 22. The face plates have numerous perforations preferably in 75 the form of radial slots 30.

The outer pan is set into a recess in a wall between adjacent uprights and the plaster is preferably removed in front of the uprights so that the flanges 17 may be 80 seated against the wood. The edges 31 of the face plate 29 are turned over projecting to the rear of the plane of the flanges 17 to be seated against the plaster or wall board as the case may be. The flanges 17 have 85 openings through which the screws may pass for securing the flanges 17 to the wall. All three pans are lined with asbestos board. The portion 33 extending along the upper wall 25 of the innermost pan extends 90 slightly farther forwardly than the portions extending along the side walls 24 as shown in Fig. 2. The face plate 28 has a flaring inner edge 28^a. The top wall thereof overlaps slightly the lining 33 and makes 95 a tight fit therewith while the free edge of the side walls abuts against the edge of the asbestos lining. The side edges have recesses 28^b sufficient to permit the entrance of air to the innermost pan to replace the air which is continuously displaced under the effects of the heat, thereby avoiding interference of air currents. The recesses 28^b 100 cooperate with the openings 11^a to allow admission of all the air necessary for complete combustion and for replacement of the air displaced.

The recesses 28^b are also more specially provided for the purpose of admitting air 105 to carry away the heat from the edge por-

tion 28^a. The relatively cool air enters and is swept by the convection currents along the surface of the edge portion 28^a thereby mitigating the heat effects upon the latter.

- 5 Notwithstanding the cooling action of such air as flows in through the recesses 28^b, the face plate 28 is heated to a considerable extent. The face plate is therefore given relatively large curved surface to provide a large radiating surface which is exposed to the cooling effect of the air surrounding it and also to the cooling effect of the air passing upwardly through the interspace between the second and the third 10 pan and out through the slots 30. Such heat as is inevitably transmitted through the walls of the innermost pan in spite of the asbestos lining causes the formation of convection currents promoting a continuous 15 flow of air. The heat conducted from the edge portion 28^a to the outer parts of the face plate 28 is thus carried off at a relatively high rate.

The continuous replacement of the warm 20 air by cool air entering from below prevents excessive heating of the air in the interspace referred to. The interspace between the outer pan and the second pan is substantially cool and serves merely as 25 a safety zone thermally separating the heater from the wood work. In order to make this thermal separation substantially complete, the face plate 29 is separate and independent of the face plate 28. As shown in Fig. 30 2 the two face plates are separated by an air space 34. The face plate 29 is supported together with the face plate 28 on the flanges 22, bolts 35 extending through both face plates and the flanges 22. On the inner surface of the face plate 29 are spacing elements 36. The bolts are drawn up until the stops 36 are firmly pressed against the rim of the face plate 28 so that the two face plates are mechanically equivalent to 35 a single face plate. Thermally, however, the two face plates are separate since the heat conducted through the bolts 35 and the stops 36 is practically negligible and is dissipated as fast as it is transmitted, by the 40 large surface of the face plate 28 and carried away by the cool air currents passing through the interspace between the outer pan and the second pan.

It is thus seen that the outer pan and the 45 face plate 29 are thermally insulated from the remaining part of the heater structure by a cool interspace.

Between the brackets 21 and the asbestos lining of the back 14 of the outer pan is 50 preferably interposed an extra layer 37 of asbestos or other heat insulating material, as indicated in Fig. 2.

The gas intake pipe 38 extends through a hole in the bottom wall 16 of the outer 55 pan and the valve control stem 39 projects

through registering slots 30 of the two face plates.

By means of the arrangement described perfect insulation and fire protection is afforded and at the same time no part of the 70 heater construction projects far into the room. The face plates being preferably white enameled cover the whole front except the radiant glowers 10. Whether the heater be in operation or not, the face plates 75 and the set of glowers present a unitary ornamental structure. While ordinarily the ornamental feature and effect upon the 80 esthetic sense has no part in a mechanical combination, the ornamental aspect in constructions of this type must be considered and must qualify to a certain extent the 85 mechanical arrangement. In this particular instance the problem of heat insulation and the problem of ornamentation have been solved interdependently so as to satisfy all requirements for a commercial and practical construction.

It will be observed that the glowers are disposed in a plane in front of the surface 90 of the wall and that by means of the edge portion 28^a of the face plate 28 the heat is carried a substantial distance into the room so that no heated air currents can flow to 95 the wall.

The heater can be easily installed, easily inspected and easily removed.

To install the heater it is merely necessary to remove the face plate 29 so that the flanges 17 may be secured to the uprights. 100 The face plate is separately secured to the flanges 22 by means of bolts. After the heater is secured in place, the face plate 29 is secured to the face plate 28 as previously described.

I claim:—

1. A gas heater of the wall heater type, comprising a set of radiant glower elements, a casing having a heat-insulating lining, surrounding the set of glowers, a second casing 110 having a heat-insulating lining surrounding the first casing in spaced relation defining an interspace, a third casing having a heat-insulating lining, surrounding the second casing in spaced relation defining an interspace, 115 a face plate spanning the first and second casing and having a large number of perforations in communication with said first interspace, a second face plate spanning the second and third casing, having a large 120 number of perforations in communication with the second interspace and presenting together with the first face plate the appearance of a single face plate, means for mechanically interconnecting the two face plates so that they are thermally substantially independent of each other, and mechanical connections between the casings 125 offering substantially no resistance to the flow of air through the interspaces. 130

2. Arrangement according to claim 1 in which the first face plate is curved defining a flaring edge portion extending outwardly from the free edge of the first casing, the edge adjoining the first casing having recesses admitting air from the first interspace to the glower space.
3. Arrangement according to claim 1 in which the inner edge of the second face plate is disposed forwardly of the outer edge of the first face plate and spaced a substantial distance therefrom and in which the means for interconnecting the two face plates include spacing elements for maintaining a definite distance.
4. A gas heater of the wall heater type, comprising an outer casing open at its front and having lateral flanges at its front edge for attachment to a wall, another casing spaced from the said casing defining an interspace, connections between the back of the first casing and the back of the second casing, said connections having webs extending in vertical direction, a third casing spaced from the second casing and having at its front edge lateral flanges, connections between the back of the second casing and the back of the third casing, said connections having webs extending in vertical direction, a set of glowers mounted in the third casing, a face plate bridging the front edges of the second and third casings and secured to the flanges of the former and a face plate bridging the first and second casings and secured to the first face plate.
5. Arrangements according to claim 4 in which the connection between the two face plates is such that they are thermally substantially separated from each other.
- In testimony whereof, I affix my signature.

JOHN H. GRAYSON.
